CLAIM

We claim the ornamental design for a spacer between pole and cross-arm, as shown.

DESCRIPTION

FIG. 1 is a perspective view of the invention with the broken line showing of a pole and a cross-arm being for illustrative purposes only and forming no part of the claimed design; FIG. 2 is an enlarged front elevational view.

FIG. 3 is a rear elevational view.

FIG. 4 is a top plan view.

FIG. 5 is a side elevational view with the opposite side being a mirror image thereof; and,

FIG. 6 is a bottom plan view.
